UNITED STATES PATENT OFFICE.

KARL BUXTBAUM, OF PHILADELPHIA, PENNSYLVANIA.

NEEDLE THREADER.

Application filed February 14, 1928. Serial No. 254,239.

This invention relates to improvements in means for inserting thread into sewing needles and has for an object, among others, to provide a device of simple construction in 5 the use of which the thread may be drawn through the eye of a needle without any particular care or skill on the part of the operator, thereby eliminating the objections of the usual threading operation.

10 The invention contemplates certain features of construction, combinations and arrangements of elements novel to the needle threading art, whereby certain important and well defined advantages are obtained.

15 One of said advantages is that my device can be used with both ordinary and sewing machine needles without any change in construction. Another advantage is that my device can be mounted on a finger like a ring, 20 leaving the hands free for the needle threading operation. Still another advantage is that my device can be made from blanks which may be easily stamped from metal, celluloid or other suitable material. Yet another advantage is that the needle catcher or the threading element may be replaced 25 with another without changing any other element of the device.

With these and other objects in view, important though not indispensable features of my invention relate to the provision of supporting means for the needle threader; a separable needle threading element, or needle catcher made from a metal stamping 30 and a guide channel to hold the needle in position for the needle threading operation.

I have illustrated the invention in the accompanying drawing in which Figure 1 is a front elevation of one embodiment of my 40 device showing the needle in needle threading position.

Figure 2 is a side elevation thereof.

Figure 3 shows the blanks for making said embodiment.

45 Figure 4 is a plan view of a modification and Figure 5 shows the blanks for making the modification.

To make the embodiment of my device shown in Figure 1, blank A is bent to form 50 the two horizontally parallel arms 1 and 2; the connecting curved portion 3; the vertical portion 4 and the ring or annular shaped portion 5. In bending the blank, care should be taken that the apertures or slots 6 and 7 55 are in vertical alinement. Then the blank B is bent along the dotted lines to form the

two vertically parallel portions 10 and 11 and the two horizontally parallel portions 8 and 9 and slipped on the elements 1 and 4 as shown in Figure 2. The blank C is then 60 bent around the parallel arm 2 to form a clamping element 12. To complete the device, the blank D which is provided with a hook 13 is bent on the dotted line to form a tab and inserted from below through the 65 two alined slots 6 and 7. Then the clamping element 12 is shifted in position so that the tab on the end of the catcher is clamped between the bottom thereof and the arm 2. As shown in Figure 2, the ends of the blank C 70 are spaced sufficiently apart to allow the clamping element to be shifted into clamping position.

To use my device the needle to be threaded which is denoted by "n" is placed with its 75 eye over the hook 13 of the needle catcher and with its shank in the guide channel 14 formed by the elements 4 and 8. A thread is looped and drawn taut through the hook 13. Removing the needle from the device automatically threads the needle.

During the threading operation the threader may be supported in any suitable way. It is here shown as being provided with a ring shaped end 5 so that it may be slipped 85 on a finger, but it may be made with a clamp so that the device may be fastened or attached to a coat lapel or to a thimble.

To further simplify my device, I may make it from two blanks A' and B' as shown in 90 Figure 5, the blank B' serving the functions of blanks B and C and part of the blank A. To assemble the device of this modification, the blank B' is bent upon the dotted lines to form two vertically parallel arms 4' and 8' which form the guide channel 14' in the finished device. The intermediate portion of the blank is bent to form two horizontally parallel arms 20 and 21, the latter arm being shown in dotted lines in Figure 4. In this 95 modification the blank A' is provided with only one slot 6' as the other is not necessary. The blank A' is bent to form two parallel arms 1' and 2' and the ring 5 in a similar manner as in the first embodiment. The bent blank B' is then slipped on the arm 1' from the left and shifted to the extreme right so that the slot 6' is entirely uncovered. The needle catcher D is then inserted in the slot 100 from below and the bent blank B' is shifted to the left to clamp the tab of the needle catcher. The blank B' is provided with a

reentrant or cut out portion 25 to provide ample space for the needle catcher.

Both embodiments of my invention are used in the same manner and both may be used to thread sewing machine needles. In threading sewing machine needles the device is held vertically and the needle catcher is inserted into the eye of the needle instead of vice versa. The thread is then looped and drawn taut around the catcher which is then removed from the eye of the needle, thus threading the needle.

While in order to comply with the statutes, the invention has been described in language more or less specific as to certain structural features, it is to be understood that the invention is not to be limited or restricted to any specific details, but that the means and constructions herein described comprises but two modes of putting the invention into effect, and the invention is therefore claimed broadly in any of its possible forms or modifications within the scope of the appended claims.

1. As an article of manufacture, a needle threader comprising a U shaped support-

ing member having a slot in one of its arms, a separable threading element extending through the slot in said arm and a clamping member for holding said threading element in position and consisting of a slideable member mounted on said arm and provided with spaced arms for holding the shank of a needle in threading position.

2. As an article of manufacture, a needle threader comprising a relatively narrow strip forming a support, said strip being provided with a slot, a separable threading element extending through said slot and clamping means slidably mounted on said narrow strip to permit the insertion or removal of the threading element from said slot.

3. A needle threader as defined in claim 2, said device being provided with a guide channel for holding a needle in threading position, said clamping means and said guide channel being formed integrally with each other.

In testimony whereof I affix my signature.

KARL BUXTBAUM.
